C. J. NASH

DRAFT RIGGING FOR RAILWAY CARS

Filed Aug. 24, 1926

UNITED STATES PATENT OFFICE.

CHARLES J. NASH, OF CHICAGO, ILLINOIS, ASSIGNOR TO UNIVERSAL DRAFT GEAR ATTACHMENT CO., A CORPORATION OF ILLINOIS.

DRAFT RIGGING FOR RAILWAY CARS.

Application filed August 24, 1926. Serial No. 181,218.

The invention relates particularly to mechanism for transferring the stresses of draft and buffing to the frame of the car, its objects being fully hereinafter pointed out.

6 The invention consists in a structure such as is described, and is illustrated in the accompanying drawings, in which

Fig. 1 is a detail longitudinal, vertical, central section of a railway car embodying the 10 invention; and

Fig. 2 is a detail plan view of the underframing of the car, partly in section.

A pair of draft sills are shown at 10, 11, 15 of ordinary construction, each being provided at its forward end with a longitudinal slot 12 for the accommodation of the draft key 13 which connects the coupler butt 14 with the yoke 15 for enclosing the draft gear 16. The parts 13 to 16 are of any ordinary and pre- 20 ferred form, the draft gear shown for the purposes of illustrating the invention being of the Westinghouse type, the rear end of the casing of the gear being laterally extended as shown at 17 to serve as a follower. The forward fol- 25 lower 18 is of the ordinary plate type.

Attached by suitable means such as rivets, to the forward end of each of the draft sills 10, 11, is a draft lug 19 slotted as shown at 20 for the accommodation of the key 13, its slot being surrounded by a flange 21 which fits within the sill slot 12.

A pair of buffing lugs 22, 23 are attached to the sills 10, 11 by rivets or other suitable means in position to engage the rear end 17 of 30 the draft gear when the latter is in release, and to sustain the shocks of buff.

Each of the buffing lugs is provided with a forwardly projecting extension 24, the portion thereof which is in advance of the range of movement of the follower element 17 being 40 provided with inwardly offset longitudinal ribs 25 which not only strengthen the lug element but also serve as lateral guides for the draft gear. The forward extension 24 of the buffing lugs terminates as an abrupt shoulder 45 26 positioned to serve as a limiting stop for the inward movement of the forward follower 18. The portions of the draft sills lying between the draft lugs 19 and the forward end 26 of the buffing lugs are clear and unob- 50 structed, thereby permitting the use of a follower 18 substantially equal in width to the space between the inner faces of the two sills, and thus having a wide bearing upon the draft lugs. 55

I claim as my invention:

A draft rigging for railway cars comprising, in combination a draft gear casing having follower shoulders, and a pair of buffing lugs cooperating with such shoulders and having forward extensions for guiding the casing, the forward end of such extensions forming stop shoulders for engaging a follower, said stop shoulders being positioned in advance of the end of the gear casing, so that 60 the follower cannot engage the casing on buff until after it has engaged the stop shoulders. 65

In testimony whereof I affix my signature.

CHARLES J. NASH.
